UNITED STATES PATENT OFFICE

ADOLPH O. GOODYEAR, OF CLEVELAND, OHIO

LOUD-SPEAKER

Application filed July 5, 1928. Serial No. 290,300.

This invention appertains to the art of sounding devices wherein electrical currents are transformed into sound values through the medium of a vibrating diaphragm which is caused to vibrate in accordance with a varying electrical current. These devices are coming into extensive use in connection with radios inasmuch as it is common practice to avail of a loud speaker together with 10 ordinary radio receiving apparatus.

To the end of attaining to the greatest degree feasible, quality, nicety, and definition of the tone produced by the sounding device, I propose to provide a device of this character wherein a plurality of vibrating diaphragms are employed and wherein these diaphragms are maintained taut to a degree heretofore unattained in this art.

In carrying out my inventive thoughts 20 into an actual embodiment thereof, I employ a main sounding drum consisting of spaced diaphragms together with sounding posts connecting the latter together so that they may vibrate in unison, and in addition a secondary vibrating diaphragm which is extremely taut and which is operatively connected with one of the first mentioned diaphragms so that vibrations of the former are transmitted to the latter through the connecting means which takes the form of so 25 called sounding posts. By interposing the electro-magnetic instrumentalities between the extremely taut diaphragm and the main sounding drum, vibrations of both are created in unison and due to the high degree of tautness in the diaphragm spaced from the sounding drum, fineness in quality of the tone of the sound produced is afforded.

Particular features of the invention reside 30 in the construction of the taut diaphragm together with its mounting on the main sounding drum, notably in the means employed for obtaining the desired degree of tenseness and tautness required.

The vibrating diaphragm hereinbefore described is operatively connected with one of the diaphragms of the main sounding drum through the medium of two sounding posts which are somewhat spaced apart. Inasmuch as vibrations are transmitted by these 35 posts to a diaphragm of the sounding drum at spaced points, I have divided this diaphragm of the sounding drum into two parts so that vibrations of one may not interfere to any extent whatsoever with vibrations of the other, thereby enhancing to a still further extent, the naturalness of the tone produced. In the construction of the sounding device provided by this invention, the taut vibrating diaphragm is provided with members 40 which are adapted to be influenced by electro-magnets to cause vibration of the former, the electro-magnetic instrumentalities being spaced very slightly from the member carried by the diaphragm, and these electro-magnetic instrumentalities are mounted on a panel which is carried by the sound drum, and noteworthy features of the invention lie in the mounting of this panel on the sounding drum as well as the particular construction 45 and arrangement of the magnetic instrumentalities. It is an object of the invention to provide means for adjusting the relationship between the panel carrying the electro-magnetic means and the sounding drum, and to this end an adjustable screw joins the lower diaphragm of the sounding drum with the panel and this screw is provided with suitable operating means for causing rotation of 50 the same to vary the distance between these parts.

With these and other objects in view as will in part become apparent and in part be hereinafter stated, the invention comprises certain novel constructions, arrangements, 55 and combinations of parts as will be subsequently specified and claimed.

For a full and more complete understanding of the invention, reference may be had to the following description and accompanying drawings, in which:

Figure 1 is a plan view of the sounding drum with the upper vibrating diaphragm, electro-magnetic instrumentalities, and its carrier panel removed therefrom.

Figure 2 is a bottom plan view of the instrument shown in Figure 1.

Figure 3 is a front view of the same.

Figure 4 is a transverse section taken through the entire instrument.

Figure 5 is a longitudinal section taken about on the line 5—5 of Figure 2.

Figure 6 is an enlarged detail showing in perspective of the magnetic instrumentalities together with the panel on which they are mounted.

While a preferred specific embodiment of the invention is herein set forth, it is to be understood that I am not to be limited to the exact constructions illustrated and described, because various modifications of these details may be provided in putting the invention into practice within the purview of the appended claims.

Generally speaking, my novel sound producing device comprises a main sounding device designated A, a taut vibrating diaphragm referred to generally by the reference character B, and the electro-magnetic instrumentalities interposed between the parts A and B and denoted by the reference character C.

The main sounding drum A is made up of an annulus 1 which carries on each edge diaphragm 2 and 3. These diaphragms are preferably made from some suitable wood which in fact is the material universally availed of throughout the construction of the instrument, with the exception of the metal employed in the electro-magnetic instrumentalities and certain metallic connecting rods and screws.

Diaphragm 3 is divided as indicated by the opening shown at 4, each edge of which is lined with a strip 5 while the lower diaphragm 2 is provided with a strip 6 which lies directly beneath the groove 4. A sound transmitting box 7 connects one part of the diaphragm 3 with the diaphragm 2 while a duplicate sound transmitting member 8 operatively connects the other part of the diaphragm 3 with the lower diaphragm 2.

The vibrating panel B comprises semi-circular members 9 which are joined together at certain points on their peripheries but which are spaced apart at the center thereof by a block 10 interposed therebetween which construction renders extremely taut the composite diaphragm B which is rendered still further tense by its mode of mounting on the sounding box A. Sound transmitting posts 11 are maintained on pedestals 12 carried by the diaphragm 3 of the sounding box and at their upper ends are connected by screws shown at 13 with the diaphragm B. It is noted that the sounding posts 11 are located inwardly with respect to the edges of the diaphragm B and sounding drum A. At their edges these last named parts are stressed together by screw tension connecting rods 14 which tend to draw the edges toward one another while the sound transmitting posts 11 exert a spreading effect. This construction renders extremely taut and sensible the diaphragm 3. Carried by the block 10 and

the members 9 are two metallic members 15 which are adapted to be influenced by an electro-magnetic structure to be hereinafter described.

Going on to these electro-magnetic instrumentalities C, a panel 16 is supported at its four corners by spacing members 17 which maintain the panel upraised from the diaphragm 3. It is notable that one side of the panel 16 is supported by one part of the diaphragm 3 while the other half is supported by the other part and this panel member extends over the opening 4. The panel 16 is provided with two joining posts shown at 18 which are employed to connect the instrument with suitable electric terminals. The panel 16 carries a permanent or horse-shoe magnet 19 which is held thereon by clamp members 20. Magnetic members 21 are connected with the permanent magnet 19 by a metallic connection shown at 22 and are constantly influenced by said permanent magnet. The magnet members 21 are wound with coils indicated at 23 which are adapted to receive a varying electric current thereby further influencing these magnetic members 21. It is noted that these members 15 on the diaphragm B show that variations in the magnetic force of these members cause vibrations in said diaphragm.

An adjusting screw 24 connects the panel 16 with diaphragm 2 and is operated by a wing operating member shown at 25 to vary the relative distance between these parts.

The operation of the instrument is substantially as follows:—Magnetic members 21 are constantly influenced by the permanent magnet 19 to draw the members 15 toward and thereby maintain a tension on the diaphragm B. However, the influence of the magnetic members 21 is varied by the varying electric current supplied to the instrument at the binding posts 18 and which are connected with the coils 24. This electro-magnetic arrangement causes vibrations not only in the diaphragm B but also in the panel 16 and which vibrations are transmitted to the diaphragm 3 by the members 17 and 11, vibrations of the diaphragm 3 being further transmitted to diaphragm 2 through the medium of the parts 7 and 8. In this manner the various diaphragms B, 2 and 3 as well as the panel 16 vibrate in unison to provide the necessary sound values which are rendered extremely natural by the tautness of the diaphragm B.

I wish to particularly emphasize the fact that the members 15 and 21 are spaced only a very slight distance apart and which distance may be varied by proper operation of the screw connecting member 24.

Having thus described my invention, what I claim as new and desire to secure by Letters Patent of the United States, is:

1. In a sound producing device of the class

described, the combination with a sounding drum, of a diaphragm spaced therefrom, means for rendering taut the diaphragm, and instrumentalities for transmitting vibrations of the diaphragm to the drum.

5 2. In a sound producing instrument of the class described, the combination with a sound producing drum comprising spaced diaphragms, of a vibrating diaphragm spaced 70
10 from the drum, means for transmitting vibration of the diaphragm to the diaphragms of the drum, and instrumentalities interposed between the drum and the spaced diaphragm for causing vibrations of both the 75
15 former and latter.

3. In a sound producing device of the class described, the combination with a sounding drum and a diaphragm spaced therefrom, of a panel carried by the drum in spaced relation thereto, means interposed between the panel and the drum for transmitting vibrations of the panel to the drum, and electro-magnetic instrumentalities mounted on the panel to cause the vibration of the drum and 80
20 diaphragm.

4. A sound producing instrument of the class described, comprising, in combination, a sounding drum made up of spaced diaphragms, one of said diaphragms being provided with a diametrical opening extending substantially the full distance across the same, and means for transmitting vibrations of one of the diaphragms to the other.

5. A sound producing instrument of the class described, comprising, in combination, a sounding drum, a diaphragm spaced therefrom, means for transmitting vibrations of the diaphragm to the drum, said diaphragm consisting of members joined together at 95
30 their edges and spaced apart at their center to render taut the diaphragm, and means for drawing the said edges together.

6. A sound producing instrument of the class described, comprising, in combination, a sounding drum, a diaphragm spaced therefrom, sound transmitting posts interposed between the drum and the diaphragm at points spaced from the edges thereof, and screw members at the edges of the drum and 105
40 the diaphragm for drawing said edges together against the spreading action of the sounding posts.

7. A sound producing instrument of the class described, comprising, in combination, a sounding drum made up of spaced diaphragms, a diaphragm spaced from the sounding drum, a panel carried by the sounding drum and interposed between said drum and the spaced diaphragm, means carried by 115
50 the panel for causing vibration of the diaphragm panel and drum, and connecting means for causing said vibrating motions to take place in unison.

8. In a sound producing instrument of the class described, in combination with vibrat- 120
60

ing instrumentalities of a diaphragm, said diaphragm being made up of members going together at points on their peripheries, and having means for spacing them apart at the middle thereof whereby they are rendered 70
75 taut to a high degree.

9. In a sound producing instrument of the class described, the combination with electric vibrating instrumentalities, of a vibrating diaphragm, said diaphragm comprising 75
80 wooden panels which engage one another at points along their edges, means for maintaining said engagement of the panels at said points, and means spaced inwardly from the edges of the panels for stretching the same 80
85 apart and thereby rendering the diaphragm taut.

10. A sound producing instrument of the class described comprising, in combination, a sounding drum made up of spaced diaphragms, one of said diaphragms having a slot extending diametrically thereof, another diaphragm carried by the said slotted drum diaphragm and spaced therefrom, vibrating instrumentalities carried by the said slotted 90
95 drum diaphragm whereby to effect vibrations in the portions of the said diaphragm on each side of the slot independently of each other, and adjusting means for the said vibrating instrumentalities.

In testimony whereof I affix my signature.

ADOLPH O. GOODYEAR.
